PARACHUTE

Heinz Berckmüller, Karlsruhe, Durlach, Germany
Application November 20, 1951, Serial No. 257,269

12 Claims. (Cl. 244—145)

The present invention relates to parachutes.

Parachutes of the type known before comprise, in general, long, pointed, triangular panels, very frequently twenty-eight in number, stitched together over their entire length to form the actual parachute and provided with the necessary cords. In the case of these familiar panel-type parachutes the lowest operational altitude is between approximately seventy and eighty meters. In constructing parachutes attempts have constantly been made to reduce the operational altitude to a minimum, and yet, until the present time no practical type has succeeded in achieving an altitude of less than seventy meters, apart from a few exceptional performances. The present world record for example is said to be on the order of sixty-three meters.

The object of the invention is to reduce considerably the present operational altitude.

This object is achieved by the provision of a plurality of individual minor parachutes or cells which, broadly speaking are joined together, preferably at the corners. For this purpose the minor parachutes are of hexagonal shape so that they may come into direct contact with each other without leaving any superfluous space. The entire parachute is consequently hexagonal.

It has been proved that, with such a parachute, a jump can be made from an altitude of approximately thirty meters in horizontal flight.

Further details and advantages of the invention will appear from the description which is rendered below with reference to the accompanying drawings, showing an embodiment in diagrammatic representation to give an example. In these drawings,

Fig. 1 shows the released parachute in plan view, with the individual cells or minor parachutes inflated, and certain details indicated in connection with one cell; and

Fig. 2 shows a simplified diagrammatic side view in section of the released parachute, as seen approximately along the line 2—2 of Fig. 1.

The parachute according to the invention comprises a plurality, preferably thirty-seven individual small hexagonal minor parachutes or cells 7 as may be clearly seen from Fig. 1. The number thirty-seven is necessarily arrived at by the fact that four individual cells were chosen to form each side of the hexagonal parachute proper. Each cell has a width preferably of one meter as calculated between any two parallel sides and a width of 1.15 meters between the apices of two opposed corners.

The invention is of course not limited to the figures given regarding number and dimensions of the cells. These figures give only a particularly suitable combination for the weight of a person of average size.

The individual cells 7 are joined only at the corners abutting 1, for example by sewing, while the sides extending from such corners are free throughout their entire lengths. It is due to this characteristic of the invention that the parachute is particularly easy of release, whereby the operational altitude, as compared with that of the

2

traditional type of parachute is fundamentally reduced. The minor parachutes or cells are abruptly exposed over their entire surface to the air current and are thereby practically instantaneously expanded.

5 Each individual cell acting as a minor parachute has, corresponding to its six corners, six minor shroud lines 8 each of which leads from one of the six corners of the individual cell as may be seen from Fig. 2. Each cell is cut from one piece and is therefore seamless. The six 10 minor shroud lines for each cell result from three continuous lines each of which enters at one corner of the corresponding cell and emerges at the opposite corner as indicated in dotted lines in Fig. 1. The three continuous lines cross in the center of the cell. They are by 15 preference covered by strips of material about three centimeters wide, shown in Fig. 1 in connection with one of the cells, situated on the upper surface thereof and are overstitched. The point where all three continuous lines cross is protected, for example by means of a cap, also indicated in Fig. 1, which is stitched on top. It would 20 be inadvisable to attach six separate minor shroud lines directly to each minor parachute or cell since these might tear off incident to the opening of the parachute comprising the cells.

25 A suitable length for the minor shroud lines 8 is two meters as calculated from the corners 1 where these shroud lines emerge from the corresponding cells to the point 2 where they meet. The thickness of the cord used for the minor shroud lines should be about two millimeters. The minor shroud lines are disposed at the corners of the minor parachutes to ensure that each remains in its prescribed position. Entangling of the small minor parachutes is thereby avoided. The minor shroud lines 8 are firmly bound to the main shroud lines 3 at the point 2 30 where the former meet. The main shroud lines 3 are in turn rigidly gathered together and bound by a suitable casing 4 and emerge below as two guide cords 5. The length of the main shroud lines 3 is approximately six meters from the point 2 where the minor shroud lines 8 35 meet to the cross piece 4, their thickness being about five millimeters.

40 The casing 4 has a length of about fifteen centimeters. The length of the two guide cords 5 may be on the order of fifty centimeters. At the ends of the guide cords 5 45 are snap hooks 6 of suitable size for fastening the parachute to the harness. To sum up therefore, the thirty-seven individual cells of the parachute have thirty-seven main shroud lines 3 and six times thirty-seven, that is, two hundred and twenty-two minor shroud lines 8.

45 The parachute can be packaged in a container measuring fifty by thirty-five by ten centimeters (50 x 35 x 10 cm.). The procedure for packing the parachute differs from that of the traditional panel parachute. While in the latter case each fabric panel must be carefully folded 50 over the next in packing in order to ensure successful release, the procedure in the case of the new parachute according to the invention is simpler and speedier.

55 The new parachute is completely spread out on a clean surface and the guide cords 5 fastened to a line and drawn upwards. The main shroud lines 3 and the minor shroud lines 8 are thus extended and the individual cells consequently automatically fold together. The suspended assembly of the cells or minor parachutes is gathered together in the arms of the operator and packed in the corresponding container, in a similar manner as in the case 60 of a conventional parachute. The packing of the new parachute is therefore extremely simple. It is merely necessary to raise the structure by means of a line attached to the guide cords to fold it automatically in a few seconds so as to obtain the desired package. The new parachute 65 is completely packaged in five minutes as compared

with twenty minutes required in the case of conventional parachutes, e. g., of the panel type.

As experiments have conclusively proved, the released parachute lies in a shallow arc, i. e., practically flat in the air as compared with the conventional panel type parachute which descends in the form of a huge hemisphere or dome. By virtue of the flat configuration of the descending parachute, the unpleasant and even dangerous rocking motion of the traditional type of parachute is substantially avoided and a surprisingly gentle landing is ensured.

Upon collapse of the parachute on the ground, after the descent, the individual hexagonal cells separate along their sides between the abutting and connected corners and it is therefore impossible for air currents to drag the parachute along the ground for any considerable distance as it can happen with the conventional type of parachute with fabric panels stitched together and forming a dome-shaped structure in which air currents can catch upon landing.

If an individual cell is damaged, it can be replaced simply and speedily.

Finally, the risk of accident due to the tearing of an individual cell or of a main or a minor shroud line, is very remote because the remaining cells are mutually supporting.

I claim:

1. A parachute comprising a plurality of individual equiangular hexagonal cells assembled together in edge-wise relationship to form a symmetrical structure which extends in spread-out condition in a common plane in which the apices of any three interiorly disposed individual cells are in abutment with corresponding apices of the respective adjacent cells, an individual minor shroud line extending from each apex of each cell totaling six individual minor shroud lines extending from each cell, said individual minor shroud lines being of equal length, a main shroud line for each six individual minor shroud lines which is joined therewith at the ends thereof and extends therefrom, means for gathering said main shroud lines at a common point remote from the ends of said individual shroud lines, and guide cords connected with 40 and extending from said main shroud lines.

2. The structure defined in claim 1, wherein said symmetrical structure is a generally hexagonal structure.

3. The structure defined in claim 1, comprising means for fixedly joining said individual cells only at the abutting 45 apices thereof.

4. The structure defined in claim 1, comprising thirty-seven of said individual cells, each of said cells having a

width across each pair of parallel sides which amounts to about 1 meter.

5. The structure defined in claim 1, comprising thirty-seven of said individual cells, each cell having a width 5 across each pair of parallel sides which amounts to about 1 meter, and each cell measuring between each pair of opposite apices about 1.15 meter.

10 6. The structure defined in claim 1, comprising three lines for each individual cell, each of said three lines entering its associated cell at one apex and traversing said cell and leaving it at the opposite apex thereof to form said individual minor shroud lines extending from said apices.

15 7. The structure defined in claim 6, wherein said three lines cross centrally of the associated cell, and a cap secured centrally of said cell over the crossing point of said lines.

8. The structure defined in claim 6, comprising strips 20 of material secured to said cell and extending thereacross, one such strip extending across said cell between each two apices thereof and overlying the line which traverses said cell between the respective apices.

25 9. The structure defined in claim 8, comprising a cap disposed centrally of each cell and fastened thereto to secure said lines where they intersect on their path traversing said cell.

10. The structure defined in claim 1, wherein the length of each individual minor shroud line is about 2 meters and wherein the length of each main shroud line is about 6 meters.

30 11. The structure defined in claim 1, wherein each individual minor shroud line has a diameter of about 2 millimeters and a length of about 2 meters and wherein each main shroud line has a diameter of about 5 millimeters and a length of about 6 meters.

35 12. The structure defined in claim 1, comprising means carried by said guide cords for securing them to a suitable parachute harness.
